HIGH-FREQUENCY COUPLING UNIT

Application filed May 5, 1926. Serial No. 106,827.

This invention relates generally to devices for coupling together high frequency electrical circuits and which may be incorporated in a radio frequency amplifier system.

In cascade radio frequency amplifiers it is common practice to couple together the various electron emission tubes by means of inductive transformers. Unless elaborate shielding is employed these transformers are apt to have sufficient magnetic linkage between their fields to cause feed back effects resulting in the generation of local oscillations by the amplifiers. Such local oscillations cause distortion of the signals and decrease the efficiency of the system.

It is an object of this invention to devise a coupling device which will have a concentrated magnetic field whereby interlinkage between successive stages of a vacuum tube amplifier may be minimized.

It is a further object of this invention to devise a coupling device for a system which will have substantially a constant energy transfer ratio for different frequencies within a given range.

It is a further object of this invention to devise a coupling unit especially adapted for use in the system disclosed in my prior application No. 96,290, filed March 23, 1926.

It is a further object of this invention to devise a coupling inductance embodying novel structural details which have high electrical efficiency and will be cheap to manufacture.

Further objects of the invention will appear from the following description in which I have set forth the preferred embodiment of my invention. It is to be understood that the scope of the invention is to be determined by the appended claims and the state of the prior art.

Referring to the drawings:

Figure 1 is a side elevational view of the complete coupling unit.

Fig. 2 is a cross section taken along the line 2-2 of Fig. 1.

Fig. 3 is a cross sectional view taken along the line 3-3 of Fig. 1.

Fig. 4 is a bottom view of the base structure.

Fig. 5 is a transverse vertical sectional view showing the construction of the condenser which is disposed upon the base.

Fig. 6 is a detail view showing diagrammatically the construction of the coil forms.

Fig. 7 is a wiring diagram showing the system with which the coupling unit is adapted to be incorporated.

The device comprises generally a pair of coil forms 10 and 11 which are constructed of some suitable insulating material such as a phenolic condensate product. These forms are substantially semi-cylindrical in shape, that is, each form is D-shaped in cross sectional area as shown in Fig. 2, so that when the two forms are positioned with their flat sides in spaced parallel relationship they will form substantially a cylindrical body. Upon these forms are wound three inductances, a secondary inductance S, a relatively small primary inductance L_1 and a second primary inductance L_2 . The inductance S is preferably divided equally between the two forms 10 and 11 and therefore comprises a pair of oppositely wound coils 13 and 14 which occupy the major portion of the forms 10 and 11. The inductance L_1 may be a single D-shaped coil wound in close inductive relationship to one of the coils 13 and 14. In the arrangement illustrated it comprises a single coil 15 wound on top of an insulating strip 16 which is wrapped around the lower portion of the coil 13. The inductance L_2 is preferably wound in two D-shaped coils disposed near one end of the forms 10 and 11. Thus as shown in Fig. 6 the lower portions of the forms 10 and 11 may be wound with the two series connected coils 17 and 18 to form the inductance L_2 . The curved cylindrical surfaces of the forms 10 and 11 are threaded to receive the wire of coils 13 and 14, every third turn of each coil being wound between the two preceding turns in order to secure a compact inductance.

Before proceeding further with the structural details of the device the general system with which it is adapted to be incorporated will be described. Such a system has been

illustrated in Fig. 7 and comprises a plurality of amplifier devices such as electron emission tubes 20 and 21. These tubes may be of the three-element type comprising a grid or control electrode 22, filament or electron emission element 23 and plate or anode 24. The input circuits 25 and 26 respectively of each tube are connected across the grid 22 and filament 23 of each respective tube as is customary practice. Similarly the output circuits 27 and 28 are each connected across a plate 24 and filament 23 and are energized from some suitable source of current such as B batteries 29. The input circuit 25 of the first tube is suitably coupled to a source of signal energy at radio frequency such as an antenna 31 and ground 32, an antenna inductance 33 being inductively coupled with a secondary inductance 34. The output circuit 28 may supply energy to any form of translator T.

For coupling together the output circuit 27 with the input circuit 26 in order to effect a transfer of energy, the output circuit 27 is completed through a plurality of branch impedances 1 and 2, the impedance branch 1 includes the capacitance or condenser C_1 and the inductance L_1 , the condenser and inductance being connected in series. The branch 2 is shunted across the impedance branch 1 and includes a resistance R_1 in series with the inductance L_2 . The inductance S is included in the input circuit 26. The system may be selectively tuned throughout a substantial range of radio frequency by means of variable condensers 36 and 37.

Because of the peculiar physical relationship between the various inductances the inductance L_1 is coupled relatively close to the inductance S while the inductance L_2 is coupled relatively loosely to the inductance S. In order to decrease the distributive capacitance between adjacent portions of the coils 13 and 14 these coils are connected in parallel so that the high potential end of each coil 13 and 14 is at its upper end, or at the end which is connected to the grid of the input circuit 26.

The operation of this system has been described in detail in my copending application No. 96,690, filed March 23, 1926. In general however the values of the inductances L_1 and L_2 and that of the capacitance C_1 is so selected that the reactance of the branch 1 will always be negative throughout the frequency range for which the system is adapted to be used and will decrease negatively with an increase in frequency. The natural period of the branch 2 is selected so as to be outside the frequency range, and its reactance is such that it is positive throughout the frequency range and increases with the frequency. The combined reactance of branches 1 and 2 in parallel is made negative throughout the frequency range while the

reactance of branches 1 and 2 in series is positive throughout the range. Since the resonance frequency of the branches 1 and 2 combined lies just beyond the longest wave length range, the circulatory current flowing between the branches 1 and 2 will be at a minimum when the system is tuned to low wave length but will increase to a maximum value for the longer wave lengths. Thus the lowering of the reactance of inductances L_1 and S due to a decrease in frequency is offset by an increase in circulatory current so that the current transfer ratio for the system will tend to remain constant.

The coils 17 and 18 are preferably connected in series and have their currents so directed that for circulatory currents they will produce a magnetic field tending to increase the induced current in inductance S and to add to the effect of the inductance L_1 . However, for short wave lengths where circulatory current is at a minimum transfer of energy will be effected by output current in the circuit 27 which splits and flows partly through the branch 1 and partly through the branch 2, thus causing the magnetic field set up by inductance L_2 to oppose the field of inductance L_1 . In other words, except for circulatory current, the inductance L_2 is practically in non-inductive relation to the inductance S, this being true because of the dividing up of the inductances L_2 and S into two separate coils each. The resistance R_1 merely serves to increase the decrement of the output circuit 27 in order to make the amplification ratio more nearly constant for the system. The resistance R_2 is inserted in series with the grid of tube 21; that is, between the grid and the oscillatory circuit formed by the secondary S and variable condenser 37. This resistance prevents local oscillations by decreasing the coupling between the input and output circuits afforded by the capacitance between the grid and plate of the tube. A similar resistance R has been shown as inserted in series with the grid of the tube 20. From the above it will be understood that the inductances L_1 , L_2 and S, and the resistances R_1 , R_2 and the capacitance C_1 are all a part of a coupling unit for coupling together two high frequency circuits.

To return to the structural details of the device, the coil forms 10 and 11 are mounted upon a suitable base 40 which is preferably provided with a suitable upstanding flange 41 upon its upper face. The lower ends of the forms 10 and 11 are received within a recess 42 provided upon the flange 41 whereby their inner flat sides are retained in close spaced relationship. The upper ends of these forms are connected together by means of a plate or disc 43 which is clamped to the ends of the forms 10 and 11 by suitable means such as screws 44. The condenser C_1 is disposed within the space surrounded by the flange 41. This con-

denser is preferably constructed of a plurality of circular metal discs 45 having conductor tabs 46 extending from one side thereof. The discs 45 are interleaved by a plurality of similar discs 47 provided with tabs 48 and which are separated from the discs 45 by means of circular washers 49 of mica or other suitable insulating material. The washers and discs are apertured to receive a screw 50 which threads into a presser plate 51 whereby the assembled condenser may be placed under any pressure desired to vary the capacitance between certain limits. To aid in assembling this condenser the tabs 46 and 48 are apertured to receive integral projections 53 extending upward from the base 40. Other integral projections 54 may be provided for positioning the apertured guide tabs 55 and 56 of the discs 45 and 47 respectively. The presser plate 51 may also be provided with apertures 57 to receive two of the projections 53 and 54. The conductor tabs 48 and 46 are extended out through slots 59 in the flange 41 to the terminal connections 60 and 61. The bottom face of the base 40 is also provided with a recess 63 to receive the two resistances R_1 and R_2 . These resistances are constructed similarly, the resistance R_1 comprising for example an insulating strip 64 wound with a coil of resistance wire 66. A second insulating strip 67 overlies the strip 64, the two strips 65 and 67 being clamped together and to the bottom face of the base 40 by means of screws 68. In the particular instance the screws 68 also extend up into the lower end of the forms 10 and 11, serving to clamp the same to the base. In order to conveniently make electrical connection to the coupling unit the base is provided with other terminal connectors 69, 70, 71 and 72. The manner in which the connector terminals are connected to the various elements of the unit is illustrated in Fig. 7 in which the location of the connectors has been indicated.

As the inductances are divided up into pairs of parallel coils the magnetic field of the unit will be concentrated, thus minimizing the possibility of magnetic interlinkage between two or more units. Manufacturing is facilitated since the forms 10 and 11 may be separately wound in a winding machine and then assembled.

I claim:

1. In a high frequency coupling unit, a secondary inductance coil comprising a pair of windings adapted to be tuned in resonance with radio frequency energy, a relatively small primary coil divided into two portions each portion thereof being closely coupled to one of the pair of windings constituting said secondary coil, and a second primary coil connected with said aforementioned primary windings and loosely coupled to said secondary coil.
2. In a high frequency coupling unit, a

secondary inductance formed of two coils connected in parallel, a relatively small primary coil closely coupled to one of said secondary coils, and another primary coil coupled to both of said secondary coils.

3. In a high frequency coupling unit, a secondary inductance coil, a primary inductance coil placed in close inductive relation to said secondary coil and a second primary inductance coil loosely coupled to said secondary coil, the field of said first primary coil being opposed to the field of said second primary coil for current passing through said coils in parallel.

4. In a high frequency coupling device, a pair of secondary coils of D-shaped cross section positioned with their flat sides in close parallel relation, a D-shaped primary coil closely coupled to one of said secondary coils, and another pair of coils to form a second primary inductance, said latter pair being D-shaped in cross section and loosely coupled to said pair of secondary coils.

In testimony whereof, I have hereto set my hand.

FREDERICK A. KOLSTER.
